UNITED STATES PATENT OFFICE.

WILLIAM E. NEUMANN, OF MICHIGAN CITY, INDIANA.

FLAME-SNUFFER FOR OIL-LAMP WICKS.

1,261,427.

Specification of Letters Patent.

Patented Apr. 2, 1918.

Application filed September 24, 1917. Serial No. 192,981.

To all whom it may concern:

Be it known that I, WILLIAM E. NEUMANN, a citizen of the United States, residing at Michigan City, in the county of La-
5 porte and State of Indiana, have invented certain new and useful Improvements in Flame-Snuffers for Oil-Lamp Wicks, of which the following is a specification, reference being had to the accompanying draw-
10 ings.

This invention relates to an improved flame snuffer for oil lamp wicks and has for its primary object to provide a very simple device which may be readily applied to the
15 ordinary oil lamp burner and which will not only snuff or extinguish the flame, but will also trim the wick.

It is another and more particular object of the invention to provide a device of the
20 above character embodying an attaching plate adapted to be secured upon the burner, a spring-held member pivoted on said plate and normally spaced from the wick, and operating means for said member to move the same and smother the flame, said member having a cutting edge to trim the burned end of the wick.

It is also a further general object of my invention to provide a device for the above
30 purpose which consists of relatively few parts of very simple form and which may, therefore, be manufactured at comparatively small cost.

With the above and other objects in view, my invention consists in the novel features
35 of construction, combination, and arrangement of parts to be hereinafter more fully described, claimed and illustrated in the accompanying drawing, in which,

40 Figure 1 is a sectional view through a lamp burner illustrating the preferred embodiment of my invention applied thereto;

Fig. 2 is a top plan view; and

45 Fig. 3 is a detail perspective view of the attaching plate and the pivoted flame extinguishing member.

In the accompanying drawing, I have shown a burner indicated at 5, which is commonly employed upon the ordinary oil lamp, said burner having the usual perforated plate 6 with a central opening therein through which the wick tube 7 extends. A cap or cover 8 is hinged upon the burner plate and is provided with a slot therein
55 through which the wick projects.

The present invention, in its preferred

embodiment, includes an attaching plate 9 having spaced openings through which the securing elements 10 are disposed. These elements are preferably of bendable sheet metal and have separable shank portions adapted to extend through perforations in the burner plate to be bent in relatively opposite directions against the under side of said plate, as indicated in Fig. 1. Upon one edge of the attaching plate 9, the flame extinguishing member 12 is hinged, as shown at 11. This member consists of a sheet metal plate having end flanges 13 and a relatively wide, longitudinal flange 14 over which the terminals of the end flanges are angularly bent, as at 15, whereby said longitudinal flange is reinforced and lateral deflection or bending of the same prevented. This flange 14 has a sharpened cutting edge 16 indicated at 17. One end of a coil spring 18 is attached to the pivoted flame extinguishing member, the other end of said spring being attached to the burner plate. To one of the end flanges 13, a wire 19 is connected at one of its ends, said wire extending through an opening in the burner plate and having a pull chain 19 attached to its other end.

Normally, the member 12 is held in an inclined position in spaced relation to the wick tube, as shown in Fig. 1, by means of the coil spring 17. When it is desired to extinguish the flame, it is only necessary to pull downwardly on the chain 19, thereby moving the member 12 to a substantially vertical position and projecting the flange 15 thereof over the end of the wick, thus smothering and extinguishing the flame. The sharpened edge 16 of said flange cuts or trims the burned end of the wick at the same time. Upon the release of the chain 19, the member 12 is returned to its normal position by the springs. It will thus be seen that I have devised a very simple and convenient attachment for oil burners, whereby the flame may be extinguished without removing the lamp chimney, and which will also keep the wick properly trimmed. The device may be readily attached to the ordinary oil lamp burner without necessitating any alterations whatever therein. In view of the relatively few parts comprising the attachment, and the simple form thereof, it is further apparent that the device can be produced at small manufacturing cost.

While I have herein shown and described the preferred construction and arrangement of the several elements of the device, it is to be understood that the same are susceptible of considerable modification therein and I, therefore, reserve the privilege of adopting all such legitimate changes as may be fairly embodied within the spirit and scope of the invention as claimed.

Having thus fully described my invention, what I desire to claim and secure by Letters Patent is:

A flame extinguisher for lamp burners comprising a plate adapted to be pivotally mounted upon the burner adjacent one side

of the wick tube and having angular flanges on its opposite ends and a relatively wide flange on one of its longitudinal edges, said end flanges being bent over and upon the ends of the latter flange and said latter flange having its projecting longitudinal edge sharpened, and operating means connected to one of said end flanges.

In testimony whereof I hereunto affix my signature in the presence of two witnesses.

WILLIAM E. NEUMANN.

Witnesses:

J. J. WATSON,
FRED C. NEUMAN.
